TAKE-UP MECHANISM FOR LOOMS

Filed Jan. 28, 1928

UNITED STATES PATENT OFFICE

CARL D. BROWN, OF HOPEDALE, MASSACHUSETTS, ASSIGNOR TO DRAPER CORPORATION, OF HOPEDALE, MASSACHUSETTS, A CORPORATION OF MAINE

TAKE-UP MECHANISM FOR LOOMS

Application filed January 28, 1928. Serial No. 250,187.

This invention relates to the take-up mechanism of a loom. It is very important that the take-up mechanism shall act uniformly and surely during the weaving of the cloth.

5 Any uneven movement of the cloth as it is taken up, especially in occasional backward slippage of the cloth, results in an imperfect product. Such slippage may be due to a wide variety of causes. If, for example, the 10 cloth presents a soft or yielding surface such as a terry or pile fabric, or if, for example, the cloth presents a smooth surface which is not readily gripped by the take-up roll surface, there may be backward slippage of the 15 cloth.

The present invention provides two positively driven take-up rolls located beneath a transverse bar which may be fixed or rotatable and may be adjacent to, or a part of, the 20 breast beam of a loom, around which the cloth passes from the fell. With the cloth passing from the transverse bar around and between the two positively driven rolls and thence to the usual cloth roll upon which it 25 is wound, each of the two surfaces of the cloth engages a positively driven take-up roll and each surface engages a wide segment of the corresponding take-up roll. Thus the take-up mechanism has a very firm hold on 30 the cloth, whatever may be its character or surface, and even when the take-up rolls present relatively smooth peripheral surfaces, the cloth is still gripped and taken up in such a way as to prevent backward 35 slippage and insure uniform and even weaving.

The object of the invention is therefore to provide a take-up mechanism involving two positively driven take-up rolls mounted beneath the transverse bar and so related that the desired results are secured.

The present invention also involves as a subsidiary feature a slight differential in the peripheral speed of the take-up rolls, so 45 that the main take-up roll or the latter of the two rolls around which the cloth passes and is taken up moves at a slightly greater peripheral speed than the other or auxiliary take-up roll. Under some circumstances 50 this is desirable as further insuring against

any backward slippage of the cloth around the auxiliary take-up roll or the first take-up roll to which the cloth passes from the transverse bar.

The nature and objects of the invention 55 will appear more fully from the accompanying description and drawings and will be particularly pointed out in the claims.

As the invention is concerned solely with the take-up mechanism and is applicable to a wide variety of looms and as the general construction and operation of such looms and the relation of the take-up mechanism thereto is well known and familiar to those skilled in the art, it is only necessary to illustrate 60 and describe a portion of one form of loom in connection with a preferred embodiment 65 of the invention.

In the drawings:

Fig. 1 is a somewhat diagrammatic view 70 in vertical cross section and side elevation showing the forward upper portion of a loom with a preferred form of the invention embodied therein.

Fig. 2 is a front elevation of a portion of 75 the loom showing the same construction.

Fig. 3 is a detail to illustrate a variation in the periphery of the take-up roll.

Fig. 4 is a diagrammatic view showing a 80 slightly different arrangement of the path of the cloth.

Fig. 5 is another diagrammatic view showing a third arrangement of the path of the cloth.

The take-up mechanism of a loom is a very 85 important mechanism because the degree of perfection with which the cloth is woven depends upon its uniformity and accuracy of operation. If the cloth be taken up irregularly, the cloth itself will be woven irregularly and will not be perfect. A great deal of difficulty is experienced, especially in connection with some types of cloth, in securing the required action of the take-up mechanism upon the cloth. If, as has already been noted, the cloth being woven presents a terry or pile surface, or if it presents an unusually smooth surface, or if for any reason the cloth is with difficulty gripped and held by the peripheral surface of the take-up roll, there 90 95 98 102 106 110 114 118 122 126 130 134 138 142 146 150 154 158 162 166 170 174 178 182 186 190 194 198 202 206 210 214 218 222 226 230 234 is likely to be backward slippage occurring at irregular intervals and producing highly undesirable results.

The present invention by a very simple and yet effective means is found in practice to insure uniformity and accuracy in taking up cloth of various types. The invention depends chiefly upon the use of two positively driven take-up rolls located beneath a transverse bar around which bar the cloth is led from the fell. By passing the cloth from this bar around and between these two positively driven take-up rolls, it is found that the cloth is firmly gripped and held by the take-up rolls. The location is such that cloth necessarily passes around large segments, that is more than half the periphery, of each take-up roll and furthermore, the two sides of the cloth are each presented to a positively driven peripheral surface of a take-up roll. The taking up action under some conditions may further be assisted by causing the periphery of the latter of the two take-up rolls to move at a slightly greater speed than the periphery of the other take-up roll.

In the construction illustrated, the usual side frames 1 of the loom are shown as connected at the front by a transverse bar 2 which may be fixed or rotatable, but is here shown as a fixed bar adjacent, or forming a part of, the usual breast beam. The cloth 3 illustrated in Fig. 1 is indicated much exaggerated in thickness and of the terry type of weave presenting pile loops at both surfaces.

Beneath the transverse bar 2 is located the main take-up roll 4 journaled on the shaft 5. This shaft 5 carries the pinion 6 driven by a gear 7 positively rotated from the driving shaft of the loom or in any other suitable manner.

Above the main take-up roll and behind and beneath the bar 2 is located the auxiliary take-up roll 8. This roll is also positively driven. In the form illustrated, the positive drive for the auxiliary take-up roll is secured by a pinion 9 on the shaft 10 of this roll meshing with a gear 11 on the shaft 5 of the main take-up roll. Usually the two take-up rolls are so geared together that their peripheral surfaces travel at the same speed.

A suitable cloth roll 12 upon which the cloth is wound is mounted in the usual manner upon a shaft 13 carried by vertical slides 14 so that as the diameter of the cloth wound on the cloth roll increases, the cloth roll moves downwardly, the rotation of the cloth roll being effected by peripheral contact with the main take-up roll. As is usual in this construction, the shaft 13 of the cloth roll is provided with a pinion 15 which at the beginning of the operation meshes with the gear 11 on the main take-up roll and insures the rotation of the cloth roll at the start. As the cloth is wound on the cloth roll, this pinion 15 moves out of mesh with the gear 11.

A guide bar 16 which may be fixed or rotatable is mounted in the side frames behind the main take-up roll and beneath the auxiliary take-up roll and around this the cloth may or may not be passed as required by the particular conditions existing.

Under some conditions it may be desirable that there be a slight differential in the peripheral speed of the two take-up rolls. If the periphery of the main take-up roll moves very slightly faster than the periphery of the auxiliary take-up roll, especially when a pile fabric is being taken up, it serves further to prevent any backward slippage of the cloth on the auxiliary take-up roll. This differential in speed must be very slight and it may be secured by any desired means, but usually it will be sufficient, without altering the gears, to increase the diameter of the roll 4, as shown in Fig. 3, by winding additional layers of paper or other surfacing material 17 thereon.

In the operation of the take-up mechanism as illustrated in Fig. 1, the cloth 3 passes from the fell around the transverse bar 2, thence back and around the auxiliary take-up roll 8, thence forwardly and around the main take-up roll 4, thence upwardly and around the guide bar 16 and thence to the cloth roll 12 at a point well in advance of the bite between the cloth roll and the take-up roll by which it is driven.

It will be seen that with this arrangement, the cloth encircles a very large portion of the peripheries of the two take-up rolls, that one surface of the cloth engages the periphery of the auxiliary take-up roll 8 and the opposite surface engages the periphery of the take-up roll 4, and that the peripheries of the two take-up rolls are slightly separated to prevent any calendering or rubbing of the cloth.

Thus the cloth is very firmly engaged by both take-up rolls and uniformly and accurately fed without injury to either surface.

The surfaces of the take-up rolls may be finished in any suitable manner depending upon the cloth being woven and are shown in Fig. 2 as covered with fine sandpaper, such as usually employed.

In Fig. 4 is illustrated a slightly different arrangement. Here the cloth 18 after passing around the transverse bar 2 passes rearward and around the auxiliary take-up roll 8, thence forwardly and around the main take-up roll 4, and thence directly to the cloth roll 12. In Fig. 5 the cloth 19, after passing around the transverse bar 2, passes downwardly and around the main take-up roll 4, thence up and around the auxiliary take-up roll 8, thence over the guide bar 16 to the cloth roll 12. In this construction when it is desired to have a slight differential in the peripheral speed of the two take-up rolls, the auxiliary take-up roll 8 will have a slightly greater peripheral speed than

the main take-up roll 4 because the cloth passes from the transverse bar first to the main take-up roll.

There is thus afforded by the arrangement 5 of the cloth with respect to the take-up rolls and guide bar means for varying more or less the extent to which the cloth is engaged by the peripheral surfaces of the two take-up rolls. But in all cases it will be observed 10 that the cloth passes first around the transverse bar and from thence around and between in succession two positively driven take-up rolls located beneath the transverse bar.

15 When, as shown in Fig. 1, a terry or pile fabric is being woven, it is frequently desirable to give an initial set in the direction of the pile loops so that as they lie on the surface of the take-up rolls they will lie in the same direction. To secure this result, the 20 transverse bar 2 in Fig. 1 is shown as presenting at the top a ridge bar 20, which bar presents a rear pile deflecting edge or corner 21. This edge, acting against the pile 25 loops of the under surface of the cloth, gives them a definite set.

Having thus described the invention, what is claimed as new, and desired to be secured by Letters Patent, is:

30 1. A take-up mechanism for looms comprising a transverse bar, a positively driven main take-up roll beneath the bar, a positively driven auxiliary take-up roll beneath and behind the bar, the said take-up rolls 35 being journalled in bearings maintaining the roll peripheries separated, and a cloth roll beneath the main take-up roll driven by a peripheral contact therewith, the said elements being so related that when 40 the cloth is led from the fell around the bar, around and between the main and auxiliary take-up rolls and thence around the cloth roll, the two faces will be engaged by segments greater than half the peripheries of 45 the take-up rolls and the cloth will be wound on the cloth roll and fed thereto well in advance of the line of peripheral contact with the take-up roll.

2. A take-up mechanism for looms comprising a transverse bar, a positively driven main take-up roll beneath the bar, an auxiliary take-up roll beneath and behind the bar and above and geared to the main take-up roll, said take-up rolls having bearings fixed 55 in position to space the rolls slightly apart, and a cloth roll beneath the main take-up roll driven by a peripheral contact therewith, the said elements being so related that when the cloth is led from the fell around 60 the bar, around and between the main and auxiliary take-up rolls and thence around the cloth roll, the two faces will be engaged by segments greater than half the peripheries of the take-up rolls and the cloth will be 65 wound on the cloth roll and fed thereto well

in advance of the line of peripheral contact with the take-up roll.

3. A take-up mechanism for looms comprising the construction defined in claim 1, together with a guide bar at the rear of the main take-up roll and beneath the auxiliary take-up roll over which the cloth is led before its passage to the cloth roll to cause the cloth to engage nearly the entire periphery of the main take-up roll.

4. A take-up mechanism for looms comprising a fixed transverse bar around which the cloth is led from the fell, two positively driven take-up rolls beneath and below said transverse bar geared together and having their peripheral surfaces spaced slightly, the cloth passing from said bar rearwardly around and between said rolls, a guide roll positioned to wrap the cloth around one of the take-up rolls for the major portion of its surface and a cloth roll beneath the take-up rolls driven by peripheral contact with one thereof and to which the cloth passes from said guide roll.

5. A take-up mechanism for looms comprising a transverse fixed bar, a positively driven main take-up roll beneath the bar, an auxiliary take-up roll spaced slightly therefrom above and geared to said main take-up roll and behind and adjacent to said transverse bar, whereby when the cloth is led from the fell around said transverse bar over said auxiliary take-up roll and between the two take-up rolls both faces of the cloth will be engaged by the major portion of both the bar and the auxiliary take-up roll, a guide roll positioned relatively to said main take-up roll to cause a maximum wrap thereabout, and a cloth roll beneath said take-up rolls driven by peripheral contact with said main take-up roll and to which the cloth passes from said guide roll.

6. A take-up mechanism for looms comprising a transverse bar around which the cloth is led from the fell, two positively driven take-up rolls beneath the bar around and between which the cloth passes successively from the bar, a cloth roll to which the cloth passes from the take-up rolls and upon which it is wound, and a guide bar around which the cloth passes after it leaves the take-up rolls and situated with respect to the cloth roll to direct the cloth into engagement with said cloth roll at a point well in advance of the bite between the cloth roll and the take-up roll.

In testimony whereof, I have signed my name to this specification.

CARL D. BROWN.
